UNITED STATES PATENT OFFICE.

HAROLD Y. PRENDERGAST, OF BROOKLYN, NEW YORK.

SOUND BOX.

Application filed May 11, 1922. Serial No. 560,124.

To all whom it may concern:

Be it known that I, HAROLD Y. PRENDERGAST, a citizen of the United States of America, residing at Brooklyn, in the county of 5 Kings and State of New York, have invented certain new and useful Improvements in Sound Boxes, of which the following is a specification.

This invention relates to sound boxes of 10 that type wherein a sounding board is interposed between the diaphragm and tone arm, and is directed to providing a yielding pressure means, whereby the diaphragm is held against undue vibration.

15 The improvement is directed particularly to providing a simple means for holding the sounding board normally under tension involving a tubular projection from the cover of the sound box and a sleeve member having sliding cooperation with the projection, the sleeve member having a flange between which and the cover there is arranged an 20 expansible spring, coiled about the sleeve and tubular projection. This construction provides for holding the sounding board 25 under such tension that it is responsive to vibrations of the diaphragm in its sound amplifying effect, and with the specific construction provided, it is not absolutely essential that the sounding board be of an inherently resilient nature.

The invention is illustrated in the accompanying drawings, in which:

Fig. 1 is a sectional view through a sound 35 box constructed in accordance with the present invention.

Fig. 2 is a perspective view of the cover and spring holding means for the sounding board, the parts being shown separated.

Fig. 3 is a perspective view of the sounding 40 board.

The improved sound box includes the usual casing 1, having the usual annular ledge 2 forming a seat for the diaphragm 3. 45 The diaphragm in this instance is preferably of less diameter than the interior of the casing, there being a gasket 4 interposed between the diaphragm and seat, a filling gasket 5 arranged beyond the edge of the 50 diaphragm, and a gasket 6 overlying the edge of the diaphragm and the gasket 5.

A sounding board 7 is loosely arranged within the casing and is formed with a central sound opening 8. The peripheral edge 55 of the sounding board is formed in a return bend to present a narrow annular section 9,

integral of course with the sounding board, the free edge of which rests inwardly of the free edge of the diaphragm 3, so that with pressure on the sounding board, the edge of 60 said board bears, through the intermediate gasket 6, on the edge of the diaphragm to secure the necessary holding effect of the diaphragm edge.

It is to be particularly noted that the diaphragm is of less diameter than the interior of the casing, and that the edge of the sounding board rests on the diaphragm, through the intervening gasket, very close to the extreme edge of the diaphragm. The 65 diaphragm is thus secured in a manner to provide an extreme sensitiveness thereof in vibration, as such diaphragm is only held at the extreme edge by the sounding board.

The sounding board of this invention is 75 held in position for the purposes of amplifying or concentrating the sound waves and at the same time securing the diaphragm in place, by a resilient compensating means of a simple nature. For this purpose, the cover 80 of the sound box, as 10, is formed with the usual sound outlet 11, and on the inner side with an integral sleeve 12 concentric with the outlet. This sleeve is of less length than the normal distance between the cover 85 and sounding board, and a collar 13 is mounted for sliding cooperation with the sleeve. This collar which has a length greater than the normal distance between the end of the sleeve and the sounding board 90 is accurately fitted on the sleeve to permit a free sliding movement, and is formed at the edge next the sounding board with an annular projection 14. A coiled spring 15 of expansible type is arranged to encircle the 95 sleeve and collar without touching either and bear between the cover and annular projection 14. The spring is normally of such length that when the cover is in position, the end of the collar is bearing upon 100 the sounding board, and the spring is under decided compression.

Thus the sounding board and diaphragm are held in place solely through the medium of the spring when the cover is applied. 105

Claims:

1. A sound box having a sounding board, a cover, and resilient holding means between said cover and sound box, said holding means including a spring and a freely movable collar operated by said spring and bearing on the sounding board. 110

2. A sound box, a diaphragm therein, a sounding board having an inturned edge to bear upon the extreme edge of the diaphragm, a cover for the sound box, and resilient holding means between said cover and sounding board, said holding means including a spring and a freely movable collar operated by said spring and bearing on the sounding board.
10. 3. A sound box having a sounding board and formed with a wall outlet sound passage, a collar freely slidable on said wall
- passage and bearing on the sounding board, a coiled spring interposed between said collar and a fixed part of said wall passage. 15
4. A sound box having a sounding board, a cover having a wall sound outlet, a collar freely slidable on the wall of the outlet and having an annular projection, said collar being adapted to bear on the sounding board, 20 and a spring bearing between the cover and annular projection of the collar.

In testimony whereof I affix my signature.

HAROLD Y. PRENDERGAST. [L. S.]
